DESIGN FOR A DRESS

Ronnye Ryan, St. Louis, Mo.

Application May 30, 1944, Serial No. 113,816

Term of patent 3½ years

(Cl. D3—26)

To all whom it may concern:

Be it known that I, Ronnye Ryan, a citizen of the United States of America, residing in the city of St. Louis and State of Missouri, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

I claim:

The ornamental design for a dress, substantially as shown.

RONNYE RYAN.
